[57] ABSTRACT

A microwave low pass filter of the so-called "waffle iron" type is disclosed. The filter utilizes die cast construction techniques and cast-in dowel holes for dimensional fidelity, close tolerances and precise alignment. The filter uses fewer parts than previous devices and can be easily assembled without the use of jigs, fixtures or special bonding techniques. Die cast construction techniques are made possible in the filter design by departing from the optimum electrical design of such components.

DIE CAST WAVEGUIDE LOW PASS FILTER

FIELD OF THE INVENTION

This invention relates to microwave filters and more specifically to microwave low pass filters of the "waffle iron" type.

DESCRIPTION OF THE PRIOR ART

In the past, the more complex microwave devices have been fabricated according to the time-honored traditions of the precision machine shop. Certainly, with the more complex and physically intricate structures the only practical way to obtain devices of the required dimensional tolerances has been by precision machining. According to these techniques waffle iron filters have been assembled from no fewer than four separate pieces, each having been previously machined of block stock brass or other material.

As is well-known, microwave filters of the waffle iron type generally comprise two identical sections of block material, each having transverse and longitudinal grooves machined therein to create a matrix of raised "bosses" or "teeth". These two sections of raised teeth are then aligned and assembled so that the teeth of each section are identically aligned with those of the other sections in the manner of a household waffle iron. A pair of sidewalls are provided to create a hollow conductively bounded structure. Typical structures of the prior art type are illustrated in U.S. Pat. No. 3,046,503 which issued on July 24, 1962 to S. B. Cohn.

In addition to the waffle iron sections and conductive sidewalls, other parts, including impedance matching sections and end flanges are required for the complete filter structure.

The main source of difficulty with such devices originates in the assembly process. Not only must each separate waffle iron section be checked for dimensional accuracy but also they must be precisely aligned at the time of assembly. If the teeth of the assembled structure are not precisely aligned, especially in the transverse direction undesirable spurious modes are generated during the operation of the device. These spurious modes in turn cause severe degradation of the electrical performance of the filter.

Proposals to modify the basic waffle iron design to attenuate the spurious modes which are generated have been made. Such modified structures are disclosed in U.S. Pat. No. 3,271,706 which issued on Sept. 6, 1966 to J. P. Rooney. Such remedies, however, do not prevent the generation of spurious modes, but rather tend to eliminate them only after they are generated. Furthermore, the modified structures tend to be somewhat larger and more complicated than the basic filter.

It is an object of the present invention to provide a microwave waffle iron filter of simplified construction.

It is another object of the present invention to provide waffle iron filters having fewer constituent parts.

Although it was proposed as early as 1948 that certain microwave components were susceptible to die cast fabrication, these methods have not been widely employed. Die casting as properly employed is known to yield castings of clean, sharp definition and close dimensional tolerances (see Ragan, *Microwave Transmission Circuits*, Vol. 9, Rad. Lab. Series, McGraw-hill, New York, 1948, p. 122).

The practical problems associated with such methods, however, frequently can be overcome only by

modifying the physical design of the die cast part. The difficulty in so doing results from the fact well-known in the microwave device art that a modification of the physical design invariably results in a modification of the electrical performance. The problem, therefore, becomes one of designing a microwave component not only from considerations of electrical and mechanical behavior but also by considerations dictated by the die casting art.

It is another object of the present invention, therefore, to modify the design of waffle iron filters to accommodate die cast fabrication techniques without adversely affecting their electrical properties.

SUMMARY OF THE INVENTION

In keeping with the principles of the present invention, these objects are accomplished by modifying the design of the waffle iron filter to accommodate die cast construction techniques. Such modifications, for example, include split sidewalls with integral flanges having cast-in dowel pin aligning holes and screw holes. Additionally, the design departs from the previously employed rectangular waveguide cross-sections and rectangular teeth by incorporating tapered waveguide walls and tapered teeth. Although the modifications in design depart from the theoretically optimum design, they result in substantially no sacrifice in electrical performance.

In addition, die cast construction techniques provide much lower manufacturing costs, improved dimensional fidelity, close tolerances, fine detail, smooth finishes, little or no machining for assembly sets and exact part-to-part duplication, all of which are required to produce high quality waffle iron filters.

BRIEF DESCRIPTION OF THE DRAWINGS

The above-mentioned and other features and objects of the present invention will become more apparent by reference to the following description taken in conjunction with the accompanying drawings in which:

FIG. 1 is a pictorial view of one of the mating halves of a waffle iron filter according to the present invention;

FIG. 2 is a longitudinal cross-section of the assembled filter in somewhat modified form; and

FIG. 3 is an end view of the assembled filter particularly illustrating the non-rectangular waveguide cross-section.

DESCRIPTION OF THE PREFERRED EMBODIMENTS

Referring more specifically to the drawings, FIG. 1 is a pictorial view of one of the mating halves of a preferred embodiment of the present invention. The part shown in FIG. 1 comprises a unitary die cast body 10 having integral end flanges 11 and 12 and an integral mounting flange 13. The complete filter comprises two such bodies joined as shown in FIGS. 2 and 3.

In the past, the designers of waveguide components and devices have attempted to avoid joints in the vicinity of maximum wall currents. With the present invention, however, the joint between the mating bodies corresponds exactly with the regions of maximum side wall currents for the fundamental mode. In order to enable the parts to be joined in this manner, body 10 has been provided with joining flanges 14 and 15 which are relatively wide with respect to overall width. Joining

flanges 14 and 15 are lapped, machined or sanded to a smooth flat finish and preferably plated prior to assembly to provide a high conductivity substantially loss-free joint. To facilitate alignment of body 10 with its mating upper half, dowel pin alignment holes 16 are provided in flanges 14 and 15. Tapped screw holes 17 also extend through these flanges to receive machine screws which provide the necessary clamping force to maintain the integrity of the assembled structure.

The internal construction of the waffle iron filter of the present invention can be readily seen in the pictorial view of FIG. 1. Again it is to be noted that an identical mating half is required to complete the assembled filter. The die cast body of FIG. 1 comprises three serially disposed sections. Proceeding from waveguide flange 11 there is shown an input impedance matching section 18, a centrally disposed filter section 19 and an output impedance matching section 20. The design of the waffle iron section 19 and impedance matching sections 18 and 20 are well-known in the art. See, for example, U.S. Pat. No. 3,046,503 mentioned hereinabove, and an article by Young and Shiffman entitled "New and Improved Types of Waffle-Iron Filters", Proc. IEE (London), Vol. 110, pp. 1191 et seq., July 1963.

For the purpose of facilitating die cast construction techniques, the design of the waffle iron filter of the present invention departs from the design dictated by the prior art and by traditional microwave engineering practice.

A taper is employed in the waveguide sidewalls as indicated by the angle α . The taper is sufficiently large to allow the die to be removed from the body 10 during the casting process without surface abrasion. The taper (usually referred to as "draft") of the waveguide wall, of course, results in a non-rectangular waveguide cross-section. By utilizing a taper or draft angle α on the order of from one-half to two degrees, it has been found that a part such as body 10 can be die cast of zinc alloy, for example, with no discernable surface irregularities caused by die removal. Additionally, it has been found that such a small departure from the optimum rectangular waveguide cross-section has no discernable adverse effect upon the electrical properties of the filter structure. In effect, the taper is so small that the resulting waveguide, although not of rectangular cross-section, is still within, or very close, to acceptable waveguide design tolerances.

The individual teeth 19 of the waffle iron filter section are illustrated in FIG. 1 to be of generally square cross-section. Depending upon the frequency range of operation of the filter and therefore the relative size of the structure, these teeth can also be tapered to facilitate removal from the die. When so tapered teeth 19 will be in the shape of frusta of right rectangular pyramids.

A modification of the structure of FIG. 1 showing the modified tooth construction is illustrated in the views of FIGS. 2 and 3. Where appropriate, like reference numerals have been carried over from FIG. 1 to designate like structural elements. In addition, the primed reference numerals designate the corresponding elements of the mated upper half of the assembled filter structure.

FIG. 2 is a longitudinal cross-sectional view of an assembled waffle iron filter according to the present invention. In FIG. 3 there is shown an end view of the assembled filter with a portion of the input impedance

matching section 18 broken away. FIGS. 2 and 3 taken together illustrate the frusto-pyramidal shaped teeth of 29 and 29' of the lower and upper mating halves of the improved waffle iron filter. In addition, the irregular hexagon cross-section of the waveguide formed by bodies 10 and 11 is illustrated in FIG. 3.

In addition to the draft or taper of the waveguide sidewalls and teeth 29 and 29' a similar taper has been designed into the integral flanges 11, 12 and 13 and 11', 12' and 13'. These tapers, although not affecting the electrical performance, are designed into the body to facilitate the die casting fabrication technique.

Although many different materials including alloys of aluminum, copper, lead, magnesium and tin can be successfully die cast, the most popular and widely used alloys are the alloys of zinc. A zinc alloy which has been successfully employed in the fabrication of the filters of the present invention is known in the trade as "ZAMAK" No. 3 (or alternatively Zinc Alloy No. 3).

Zinc Alloy No. 3 has the following composition:

Aluminum	3.5 - 4.3 percent
Copper	0.25 percent maximum
Magnesium	0.02 - .05 percent
Iron	0.10 percent
Lead	0.005 percent maximum
Cadmium	0.004 percent maximum
Tin	0.003 percent maximum
Zinc	remainder

It should be noted that the range of values one-half to two percent given for the taper angle α applies to magnesium and zinc alloys. In general, if the body is to be die cast of aluminum the taper angles should be increased to a range of approximately two to four degrees.

After casting the parts are first trimmed to remove the burrs and runners and are then sanded or machined to obtain the desired flatness of the mating surfaces. The finished castings are then plated with a high conductivity material such as silver by processes well-known in the art. The bodies are then mated with the aid of steel dowel pins and machine screws as shown in FIGS. 2 and 3.

In all cases it is understood that the above-described embodiments are merely illustrative of but a small number of the many possible specific embodiments which can represent applications of the principles of the present invention. Numerous and varied other arrangements can be readily devised in accordance with these principles by those skilled in the art without departing from the spirit and scope of the invention.

What is claimed is:

1. An improved microwave filter of the type wherein a hollow conductively bounded waveguide section is provided with a plurality of spaced conductive teeth extending from at least one wall thereof and wherein said teeth are arranged in rows and columns which are parallel and transverse to the longitudinal axis of said waveguide section, respectively, the improvement comprising:

a waveguide cross-section which is in the shape of an irregular hexagon.

2. An improved microwave filter of the type wherein a hollow conductively bounded waveguide section is provided with a plurality of spaced conductive teeth extending from at least one wall thereof and wherein said teeth are arranged in rows and columns which are parallel and transverse to the longitudinal axis of said

waveguide section, respectively, the improvement comprising:

a waveguide cross-section which is in the shape of an irregular hexagon, and wherein said teeth are in the shape of frustra of right rectangular pyramids.

3. An improved microwave filter of the type wherein a hollow conductively bounded waveguide section is provided with a first plurality of spaced conductive teeth extending from a first wall thereof and a second plurality of spaced conductive teeth extending from a wall opposite said first wall, said first and second pluralities of conductive teeth being arranged in rows and columns which are parallel and transverse to the longitudinal axis of said waveguide section, respectively, the improvement comprising:

a waveguide cross-section which is in the shape of an irregular hexagon.

4. An improved microwave filter of the type wherein a hollow conductively bounded waveguide section is provided with a first plurality of spaced conductive teeth extending from a first wall thereof and a second plurality of spaced conductive teeth extending from a wall opposite said first wall, said first and second pluralities of conductive teeth being arranged in rows and columns which are parallel and transverse to the longitudinal axis of said waveguide section, respectively, the improvement comprising:

a waveguide cross-section which is in the shape of an irregular hexagon, and wherein said conductive teeth are in the shape of frustra of right rectangular pyramids.

5. An improved microwave filter of the type wherein

a hollow conductively bounded waveguide section is provided with a first plurality of spaced conductive teeth extending from a first wall thereof and a second plurality of spaced conductive teeth extending from a wall opposite said first wall, said first and second pluralities of conductive teeth being arranged in rows and columns which are parallel and transverse to the longitudinal axis of said waveguide section, respectively, and wherein said waveguide section includes first and second stepped impedance matching sections longitudinally disposed on either side of said pluralities of conductive teeth, the improvement comprising:

a waveguide cross-section which is in the shape of an irregular hexagon.

15 6. An improved microwave filter of the type wherein a hollow conductively bounded waveguide section is provided with a first plurality of spaced conductive teeth extending from a first wall thereof and a second plurality of spaced conductive teeth extending from a wall opposite said first wall, said first and second pluralities of conductive teeth being arranged in rows and columns which are parallel and transverse to the longitudinal axis of said waveguide section, respectively, and wherein said waveguide section includes first and second stepped impedance matching sections longitudinally disposed on either side of said pluralities of conductive teeth, the improvement comprising:

a waveguide cross-section which is in the shape of an irregular hexagon, and wherein said conductive teeth are in the shape of frustra of right rectangular pyramids.
